(57) **CLAIM**

The ornamental design for electronic glasses, as shown and described.

DESCRIPTION

FIG. 1 is a perspective view showing the top, back and right sides of electronic glasses showing our new design; FIG. 2 is a perspective view showing the top, back and right sides of the electronic glasses of FIG. 1 showing temples folded.

FIG. 3 is a top plan view of FIG. 2;

FIG. 4 is a front elevation view of FIG. 1;

FIG. 5 is a back elevation view thereof;

FIG. 6 is a left-side elevation view thereof;

FIG. 7 is a right-side elevation view thereof;

FIG. 8 is a top plan view thereof; and,

FIG. 9 is a bottom plan view thereof.

The uniform dashed broken lines illustrate portions of the article and form no part of the claimed design. The dot-dash broken lines in FIG. 9 also illustrate portions of the article and form no part of the claimed design.

1 Claim, 6 Drawing Sheets
